UNITED STATES PATENT OFFICE.

FENWICK L. ELLIS, OF DARIEN CENTER, NEW YORK.

FOLDABLE IRONING BOARD.

Application filed May 16, 1925. Serial No. 30,687.

This invention relates to improvements in ironing boards or tables.

One of its objects is to provide a firm foldable ironing board having improved means for adjusting the same to various heights to suit the user.

Another object of the invention is to provide an ironing board of this character which, while simple and inexpensive to manufacture, is strong, durable and rigid in construction.

In the accompanying drawings:—

Figure 1 is a side elevation, partly in section, of an ironing board embodying my improvements. Figure 2 is a bottom plan view thereof showing the same in its folded position. Figure 3 is an enlarged transverse vertical section on line 3—3, Fig. 1. Figure 4 is a detached perspective view of the table brace.

Similar characters of reference indicate corresponding parts throughout the several views.

The improved board consists of a table 10 provided adjacent one end thereof with a pair of depending brackets 11. For the purpose of sustaining the table in a substantially horizontal position, a pair of pivotally connected main and auxiliary supporting frames 12, 13 are provided, the frame 12 being somewhat longer than the companion frame 13 and consisting of downwardly-converging bars or pivot legs 14 which are pivoted at their divergent upper ends to pivot bolts 15 carried by the brackets. As shown in Fig. 2, the converging lower ends of these legs meet and are joined together by a bolt 16. The shorter or auxiliary frame 13 consists of a pair of downwardly-diverging bars or legs 17 which are pivoted to the companion rear legs of the main frame on a transverse tie-bolt 18, spacing sleeves 19 being mounted on this bolt between the opposing faces of the legs of the respective supporting frames. As shown in Fig. 2, the converging upper ends of the legs 17 are sufficiently spaced apart to straddle the companion legs 14 in the folded position of the supporting frames.

For the purpose of adjusting the table to

various heights to suit the user, the upper ends of the legs 17 are provided with pins or studs 20 which are adapted to engage one or another of a row of corresponding openings 21 preferably formed in metallic bars 55 or strips 22 secured to the underside of the table by screws 23 or other appropriate fastenings. By swinging the auxiliary support 13 relatively to the companion support 12 and engaging the pins 20 with one or another pair of the openings 21, the table can be readily adjusted to any desired height. As shown in Fig. 1, the ends of the legs containing the pins are preferably rounded or convex and bear directly on the undersides 65 of the corresponding perforated bars 22.

To stiffen the overhanging front end of the table, a tie rod or tensioning member 24, preferably of wire and Y-shaped, is provided, which is hinged at its upper end to 70 depending ears 25 preferably formed at the front ends of the perforated bars 22, while its lower end terminates in a lateral pin or stud 26 which is adapted to interlock with one or another of a series of openings 75 27 formed in a bar 28 arranged lengthwise of the main supporting frame. As shown in Figs. 1 and 2, said bar 28 is located between the converging lower ends of the legs 14 and is fastened at its opposite ends to cross-braces 29, 30 connected to said legs. In order to prevent the tie-member 24 from becoming accidentally disengaged from the bar 28, a swinging latch-bar or guard 31 is preferably provided which is pivoted at its lower end to the corresponding end of the bar, while its upper end is adapted to enter a notch 32 formed in the cross-brace 30 to hold the free end of the bar against lateral displacement. In its operative position, shown by dotted lines in Fig. 1, this guard extends lengthwise of the bar 28 and overlies the lower end of the tie member to retain its pin in an opening of the bar, the guard being co-extensive with the row of openings 80 27 to lock the tie member in place in all 85 adjustments of the table.

After unfolding the table and its supporting frame and engaging its pins 20 with the desired openings 21 of the table, the pin 100

26 of the tie member is interlocked with a suitable opening 27 of the frame. This is done by bearing down on the overhanging front portion of the table, which causes 5 springing of that portion of it more or less and also downward deflection of the resilient front legs of the frame by the fulcruming of the table on the upper ends of the rear leg-members. While these parts are in this 10 sprung position, the pin of the tie member is interlocked with the lowest of the openings 27 reached by it, whereupon the user releases the pressure on the table. The tie member is thereby placed under tension and 15 tends constantly to draw the table and the front legs together, holding the table with considerable firmness. For this purpose, the side bars of the front leg are preferably made of comparatively resilient wood, such 20 as white ash, maple or hickory, while the table may be of basswood or pine.

When it is desired to disconnect the tie member from the bar 28, the guard is swung to the position shown by full lines in Fig. 25 1. In the folded position of the ironing-board, the pin of the tie member is adapted to engage an eye 33 depending from the underside of the table.

In order to hold the supporting frames in 30 their folded position against the table, as shown by dotted lines in Fig. 1, a spring-pressed locking bolt 34 is arranged on the underside of the table adjacent the front end thereof and is adapted to interlock with a 35 socket 35 formed in the lower cross-brace 29 of the legs 14. In swinging the leg-frames to their folded position against the underside of the table, the leg-frame 13 is first 40 disengaged from locking engagement with the table and then swung in the direction of the arrow to bring the same alongside the companion leg-frame 12, after which the latter is swung upward into locking engagement with the spring-pressed bolt 34. It 45 will be noted that in this folded position, the shorter leg frame is prevented from unfolding by reason of its upper ends abutting against the underside of the board.

By constructing and arranging the leg-frames in this manner, a three-point bearing 50 with the floor is provided, which results in the ironing-table being supported in a firm and level position. The means for adjustably connecting the leg-frame 13 with the table combined with the tie-member 24, produces an ironing board which is stiff and sturdy and can be readily handled without danger of its accidentally collapsing.

In the appended claims, the main and 60 auxiliary frames 12, 13 are together termed a folding frame; the part thereof above the frame-pivot 18 to which the table is hinged, is referred to as the inclined rear supporting member, and the part thereof above said frame-pivot, upon which the table rests, is

referred to as the inclined front supporting member.

I claim as my invention:—

1. The combination of a foldable frame including inclined front and rear supporting members, an ironing table pivoted at its rear end to said rear supporting member and normally resting on said front supporting member and overhanging the latter, means for adjustably engaging said inclined front supporting member with the ironing table at different distances from the table-pivot, and a substantially upright tensioning tie-rod connecting the table with the subjacent rear member of the foldable frame, said tie-rod 70 being attached to the overhanging portion of the table and detachably engaged under tension with the subjacent rear frame-member in the normal position of the table to draw the table and the last-named frame 75 member tightly together. 80

2. The combination of a foldable frame having members, one of which has a series of openings, an ironing table pivoted at one end to one of said frame-members, means 90 for adjustably engaging the other frame-member with the ironing board at different distances from the table-pivot, a tie-member attached to the table and provided with a lateral pin to engage one or another of said 95 openings, and a latch mounted on said apertured frame-member and overlapping the lower end of the tie member for locking its pin in place.

3. The combination of a foldable frame having members, one of which has a series of openings, an ironing table pivoted at one end to one of said frame-members, means 100 for adjustably engaging the other frame-member with the ironing board at different distances from the table-pivot, a tie-member attached to the table and provided with a lateral pin to engage one or another of said 105 openings, and a latch pivoted to said apertured frame-member and co-extensive with said series of openings to retain said pin in 110 any one of them.

4. The combination with a foldable frame having members, one of which has a series of openings in its side, an ironing table pivoted at one end to one of said frame-members, means for adjustably engaging the other frame-member with the ironing-board at different distances from the table-pivot, a substantially-upright tie-rod attached to 120 the table and provided at its lower end with a lateral pin adapted to enter one or another of said openings, and a locking latch pivoted to said apertured frame member at one end of its series of openings and extending throughout the series, said apertured frame member having a notch arranged to receive the free end of said latch to hold it from lateral displacement. 125

5. The combination with a foldable frame 130

having members, one of which has a series of openings in its side, an ironing-table pivoted at one end to one of said frame-members, means for adjustably engaging the other frame-member with the ironing-board at different distances from the table-pivot, a substantially upright tie member attached

to the table and provided at its lower end with a lateral pin adapted to enter one or another of said openings, and an eye on the underside of the table arranged to receive the pin of the tie-member in the folded position of the frame and the tie-member. ¹⁰
